United States Patent Office.

LUCIUS CARRIER, OF PROVIDENCE, RHODE ISLAND.

Letters Patent No. 67,022, dated July 23, 1867; antedated July 19, 1867.

IMPROVEMENT IN PASTEBOARD BOXES.

The Schedule referred to in these Letters Patent and making part of the same.

TO ALL WHOM IT MAY CONCERN:

Be it known that I, LUCIUS CARRIER, of the city and county of Providence, and State of Rhode Island, have invented a new and useful Improvement in making Boxes of Pasteboard, Thin Wooden Boards, or Splints, &c.; and I do hereby declare that the following is a full and exact description of the same, reference being had to the accompanying drawings making part of this specification, in which—

Figure 1 is a perspective view of a box made in accordance with my improved mode.

Figure 2 represents the improved mode of cutting and uniting the edges of parts of folded pasteboard, &c., to convert the same into a durable box.

Similar letters indicate corresponding parts in all the figures.

By the mode heretofore practised in making pasteboard boxes, a square piece was cut from each corner of the piece of pasteboard, and the rectangular flaps or pieces thus formed upon the four sides were folded against each other at their edges, and confined in such position by pasting paper inside and out. By this mode the corners of the box are only formed of the paper, and whenever the sides are subjected to slight strains the box rips down at the corners, and is thus rendered useless. This difficulty has been remedied in some measure by pasting patches of muslin over the corners of the box, under the finishing-paper, and also by removing only one-half of the square piece *a*, the corners of the box, and folding the remaining half outside of the adjoining side, and securing these parts in this position by pasting paper thereon, as described. By this mode, however, the corners of the box depend very much upon the tenacity of the paper covering for their strength, and if the part that laps upon the outside is not broken at the bend of the corner so that it will be sufficiently flexible, the overlapping will separate from the contiguous side, and thereby weaken the corner thus formed and prepare it to tear open with the first strain that is put upon it.

My improvement is intended to wholly remedy this difficulty of tearing down at the corners, and consists in cutting that portion of the material which is to form the sides of the box in such a manner as to form a flap or free strip which can be folded or bent at right angles to form the corner of the box, and which is otherwise so cut as to interlock with the adjoining edge by means of dove-tailing straps cut in the two adjoining parts, so that the corners of the box may be of the same thickness and strength as any other portion of the box; that the sides of the box may be of the same thickness all around, and that the strength of the dove-tail joint shall depend upon the firmness of the material of the side instead of upon any covering of cloth or paper pasted thereon.

In the drawings, *a*, fig. 2, is the flap or free strip, which is cut free from the corner of the pasteboard by means of a cutter of its exact counterpart in form, which cuts out a square piece of corresponding area, next to the corner square, at the same time forming a tongue or dove-tail, *s*, which exactly fits the corresponding-shaped opening or socket *s* in the said flap *a*. This flap is then bent squarely at the line *e e*, and at the lines *d d*, and the parts folding together on these lines, the fold or bend at *e e* forming the corner of the box, and the free flap *a*, uniting by means of the dove-tail strap to the side *E* of the box, which forms a full and complete side, and a corner of equal strength to any other part of the box. Over this dove-tail joint the paper may be pasted to conceal the joint and render the box ornamental, as well as to keep the two parts of the joint connected together, but without depending upon the strength of the paper to strengthen and support the sides or corners of the box.

Having described my invention, what I claim, and desire to secure by Letters Patent, is—

Making the sides and corners of pasteboard and similar boxes by cutting and bending the flap *a* or its equivalent to form the corner, and uniting the said flap with the adjoining side by dove-tailing the two parts, substantially as described for the purpose set forth.

LUCIUS CARRIER.
